US00D632659S

(12) **United States Design Patent**
Hsieh

(10) **Patent No.:** **US D632,659 S**
(45) **Date of Patent:** **** Feb. 15, 2011**

(54) **LIGHT EMITTING DIODE LAMP**

(75) Inventor: **Chung-Chuan Hsieh**, Taipei Hsien (TW)

(73) Assignee: **Everlight Electronics Co., Ltd.**, Taipei (TW)

(**) Term: **14 Years**

(21) Appl. No.: **29/361,334**

(22) Filed: **May 10, 2010**

(30) **Foreign Application Priority Data**

Nov. 11, 2009 (TW) 98305365

(51) **LOC (9) Cl.** 13-03

(52) **U.S. Cl.** **D13/180**

(58) **Field of Classification Search** D13/180; D26/2; 257/79, 80, 81, 88, 89, 95, 98, 99, 257/100, E33.058; 313/483, 498, 500; 362/555, 362/800

See application file for complete search history.

(57) **CLAIM**

The ornamental design for a light emitting diode lamp, as shown and described.

DESCRIPTION

FIG. 1 is a perspective view showing my new design;

FIG. 2 is a front elevational view thereof;

FIG. 3 is a left side elevational view thereof;

FIG. 4 is a right side elevational view thereof;

FIG. 5 is a top plan view thereof;

FIG. 6 is a bottom plan view thereof; and,

FIG. 7 is a cross-sectional view thereof, taken on line A—A of FIG. 5.

The rear elevational view thereof is a mirror image of the front elevational view in FIG. 2 and therefore is omitted.
